No 1,656. S. W. Gibbs.
Design for the Plates of a Stove
Patented Sept. 23. 1862.

Sam'l Carter

W. G. Heister

S. W. Gibbs

Des. 1656

Samuel W. Gibbs, of Albany, N.Y.
Letters Patent No. 1656, dated Sept. 23, 1862.

The schedule referred to in these Letters Patent and making part of the same.

To all whom it may concern:

Be it known that I, Samuel W. Gibbs, of the City of Albany, in the County of Albany, and State of New York, have invented or produced a new and original design for the plates comprising a Parlor Grate Stove; and I do hereby declare that the following is a full and exact description thereof, reference being had to the accompanying drawing and to the letters of reference marked thereon.

The stove is represented with all its parts in their proper places.

The design and configuration of the front plate extending from the point A, to the point B, also the design and configuration of the top blower C, the bottom blower D, the cross bar E.

The top blower C, and the bottom blower D, are removable and do not form part of the front plate.

The cross bar E, when the stove is mounted is fastened to the front plate A. B. by screw bolts and although a separate piece, forms part of the front plate A. B. when the stove is mounted in its proper shape; the design and configuration of the mouldings F, running around the outer edge and forming part of the bottom of the parlor grate stove, also the design and configuration of the fire hearth G, the leg H, and also the design and configuration of the top I, including the mouldings which run around the said top I, and which are designed by the figures 1 and 2, also the Glen or hot water cup corner J, forming the finish of the top I..

What I claim as my invention or production is the design and configuration or combination of figures and forms of the different plates composing a parlor grate stove or "Franklin Grade", as described and shown.
